(57) **CLAIM**

The ornamental design for a compartmentalized bandolier style container for gun cleaning tools and parts, as shown and described.

DESCRIPTION

FIG. 1 is an isometric view of my new compartmentalized bandolier style container for gun cleaning tools and parts;
 FIG. 2 is a top plan view thereof;
 FIG. 3 is a frontal isometric view thereof;
 FIG. 4 is a rear isometric view thereof;
 FIG. 5 is an end elevational view, the opposite end comprising a mirror image; and,
 FIG. 6 is a top plan view thereof.
